IRA SHAFFER AND CHARLES A. SMALL, OF SAN DIEGO, CALIFORNIA.

COATING AND FORMING MACHINE.

1,393,401.

Specification of Letters Patent. Patented Oct. 11, 1921.

Application filed January 20, 1920. Serial No. 352,828.

To all whom it may concern:

Be it known that we, IRA SHAFFER and CHARLES A. SMALL, citizens of the United States, residing at San Diego, in the county of San Diego and State of California, have invented a certain new and useful Coating and Forming Machine, of which the following is a specification.

Our invention relates to a machine for coating centers for candies and the like and for forming and shaping the coating and covering over the centers and the objects of our invention are: first, to provide a machine of this class which will automatically cover, and shape the covering for centers for candies and the like; second, to provide a machine of this class which will produce candies with centers and outer coating of uniform shape and size; third, to provide a machine of this class in which the centers will be rapidly covered thus facilitating the making of candies of this class; fourth, to provide a machine of this class which will operate for completely covering centers in which the covering is of a very thick substance such as soft candy and chocolate including nut kernels, cocoanut, etc.; fifth, to provide a machine of this class in which the covering substance is forced into position around the center, thus providing positive and uniform action; sixth, to provide a machine of this class in which the different operating parts operate in their proper sequence for properly covering a center and at the same time shaping a coating for candy and the like and seventh, to provide a machine of this class which is very simple and economical of construction, durable and automatic in its action.

With these and other objects in view as will appear hereinafter, our invention consists of certain novel features of construction, combination and arrangement of parts and portions as will be hereinafter described in detail and particularly set forth in the appended claims, reference being had to the accompanying drawings and to the characters of reference thereon which form a part of this application, in which:

Figure 1 is a side elevational view of our machine showing some of the parts and portions fragmentarily and minus center feeding conveyer, to facilitate the illustration; Fig. 2 is a sectional view through 2-2 of Fig. 1; Fig. 3 is a sectional view through 3-3 of Fig. 2 and showing some of the

parts in dotted lines, showing varying operating positions; Fig. 4 is an enlarged detailed sectional view of the cover forming plunger and its contiguous parts and portions; Fig. 5 is a sectional view through 5-5 of Fig. 4; Fig. 6 is a sectional view through 6-6 of Fig. 2 showing some of the parts and portions broken away and fragmentarily to facilitate the illustration; Fig. 7 is a sectional view through 7-7 of Fig. 1 and Fig. 8 is a sectional view through 8-8 of Fig. 1.

Similar characters of reference refer to similar parts and portions throughout the several views of the drawings.

The machine base 1, hopper base 2, hopper 3, cylinder 4, plunger 5, center support 6, separator member 7, separator member support 8, lower feeding plungers 9, upper feeding plungers 10, conveyer 11, segment gear 12, pinion 13, cap 14, drive shaft 15, cam members 16, 17 and 18, pulleys 19, 20 and 21, pinion 22, segment gear 23, conveyer 24, pinion 24^a, segment gear 26, segment gear 27, support 28 and gears 29 and 30 constitute the principal parts and portions of our coating and forming machine.

The machine base 1 is of the proper shape and size to support the machine and mounted on this machine base 1 is the hopper base member 2 by means of upright members 2^a which is supported some distance above the machine base 1. This hopper base 2 is preferably a casting shaped as shown, provided with downwardly converging circular walls except on one side which is flat. In this flat side are provided apertures 2^b and 2^c, shown best in Fig. 1 of the drawings. The aperture 2^b is the intake for the center to be coated and the aperture 2^c is for the exit of the surplus coating and there is also provided on the opposite side from the aperture 2^c another aperture 2^d shown in Fig. 6, adapted for the same purpose.

Secured on the upper edge of this hopper base member 2 is a hopper 3 conforming with the shape of the upper side of said base shown best in Fig. 2 of the drawings and provided with an inwardly extending flange 3^a adapted to engage the outwardly extending flanges 2^e on the base member 2 and this hopper is secured thereto by means of bolts through the flanges 3^a and 2^e. Secured in the base member 2 adjacent the flat side is the cylinder member 4, by a tight fit at its bottom end and supported by means of a

U clamp 4^a extending through the flat side of the base member 2 shown best in Fig. 6 of the drawings. This cylinder 4 is provided in its lower end with apertures 4^b 5 forming to the apertures 2^c and 2^d in the member 2 for the exit of surplus. It is also provided with an aperture conforming to the aperture 2^b in the base member 2 for the intake of the centers and with two side 10 apertures 4^e for the inlet from the hopper of the coating substance below the candy center and with two upper side apertures 4^d which serve as inlets for the coating substance above the candy center and this cylinder member 4 extends upwardly to approximately even with the top of the hopper member 3.

Reciprocably mounted in this cylinder member 4 is a plunger member 5 which is 20 cylindrical in form and it is provided in its lower end with a cup shaped portion 5^a which is adapted to form the upper portion of the outer surface of the coating and this portion 5^a is provided with apertures 5^c 25 conforming to the apertures 2^c and 2^d for exit of surplus when the plunger is down. This plunger is reciprocated by means of an arm 5^b which extends upwardly and engages the cam 17, secured to the shaft 15. 30 Secured in the upper end of the cylinder 4 is a cap 14 which is provided with an upwardly extending annular flange 14^a in which is revolvably mounted the separator support 8, which is provided with a pinion 35 13 on its upper end which is adapted to be engaged by the segment gear 12 secured on the main shaft 15 thus providing intermittent revoluble movement for the member 8. This member 8 is provided with a longitudinal slot 8^a in one side thereof and mounted in this member 8 is the separator member 7 which is provided with a curved blade 7^a on its lower end which is adapted to 40 revolve against the inner surface of the portion 5^a and separate the coating from said portion. In the slot 8^a is provided a lug 7^b adapted to permit reciprocal movement of the member 7 relatively to the member 8 but prevent torsional relative movement. 45 Reciprocably mounted in the member 7 is a candy supporting member 6 which is pointed at its extended end and extends upwardly through the member 8 and is reciprocated by the cam 17 secured on the 50 shaft 15.

Reciprocably mounted in the base member 2 are the lower feeding plungers 9 by means of rods 9^a which extend upwardly and are pivotally connected to the rocker arms 9^b 60 which are pivotally mounted on an axis 9^c secured on an extended flange 14^b of the cap member 14.

Pivotally connected to the opposite ends of the rocker arms 9^b are rods 10^a which extend downwardly and pivotally connect with

the upper feed plungers 10 which are pivotally mounted at their opposite ends in a trough member 10^b which is secured at its ends on the flange 3^a of the hopper 3 and its sides extend around the cylinder 4. These 70 rocker arms 9^b are actuated by means of a rod 9^c which extends upwardly through a support 9^d and its upper end engages a cam 16, secured on the main shaft 15.

Mounted below the base member 2 and 75 between said base member and the machine base 1 is a conveyer 11 which consists of an endless belt mounted on pulleys 21 and 21^a, shown best in Figs. 1 and 2. The pulley 21 is secured on a shaft 22^a journaled in a bearing 22^b and pivotally mounted on this shaft 22^a are side supports 11^a in the opposite end of which is journaled the axle for the pulley 21^a and the free end of the supports 11^a is actuated upwardly and downwardly by 80 means of a rod 11^b pivotally connected thereto which extends upwardly and engages a cam 18 on a main shaft 15. Secured to the supports 11^a is a transverse support 11^c which extends upwardly and supports the 85 belt 11 immediately below the lower side of the base member 2 to prevent the sagging of the belt with the pressure of the plunger member 5 in forming the coating on the candy center. Mounted on the shaft 22^a is 90 a pinion 22 which is adapted to be engaged by the segment gear 23 thus providing for the intermittent operation of the conveyer 11, this segment gear 23 is secured on a shaft 23^a and on this same shaft is secured a 100 pulley 20, upon which is a belt 20^a which connects with the pulley 19 mounted on the shaft 27. This shaft 27 is supported by a support 28 which also supports the shaft 15 and said shafts are operatively connected by 105 the gears 29 and 30. The candy centers are fed into the aperture 2^b by means of a conveyer 24 mounted on pulleys 24^a and secured in connection with the shaft of one of said pulleys is a pinion 24^b which is engaged by a segment gear 26 secured to a shaft 26^a upon which is also secured a pulley 26^b upon which is mounted a belt 26^c which extends upwardly over a pulley 27, secured on the main shaft 16. This conveyer 24 is 110 intermittently operated by the intermittent engagement of the segment 26 with the pinion 24^b.

The operation of the machine is as follows: The hopper is filled with the coating substance and the candy centers positioned on the conveyer 24 and the operating parts are timed in the proper sequence to operate as follows:

The plunger 9 is moved downwardly in 125 the hopper base 2, forcing a small quantity of the coating substance into the lower end of the cylinder 4 through the apertures 4^e and supported by the conveyer 11, then the candy center is moved into the cylinder 130

member 4 by means of the conveyer 24 through the aperture 2^b and supported on said coating substance, then the center supporting member 6 is moved downwardly 5 piercing the candy center and the plunger members 10 are then moved downwardly simultaneously with the upward movement of the plunger 9, forcing the coating substance into the cylinder above the candy center through the apertures 4^a, then the plunger 5 is moved downwardly in the cylinder 4, pressing the substance around the center and forming its outer surface, the surplus, if any, passing out through the apertures 4^b, 2^c and 2^d and may be conducted to any place desired, then the separator 7^a 15 is revolved inside the member 5^a, separating the coating from the cup shaped member 5^a by the gear member 12 engaging the pinion 13.

Then the plunger 5 and support 6 are moved upwardly releasing the center and the cam 18 moves the free end of the supports 11^a downwardly, then the segment engages 25 the pinion 22^a operating the conveyer, moving the finished product out of the way and the operation just recited is repeated.

Though we have shown and described a particular construction, combination and arrangement of parts and portions we do not 30 wish to be limited to this particular construction, combination and arrangement but desire to include in the purview of our invention the construction, combination and arrangement substantially as set forth in the appended claims.

It is obvious that various mechanisms may be used in lieu of the cams, belts and pulleys for actuating the various operating parts in 40 their proper sequence.

Having thus described our invention what we claim as new and desire to secure by Letters Patent, is:

1. A machine of the class described, including a hopper provided with downwardly converging walls, a cylinder positioned vertically in said hopper provided with oppositely disposed apertures in spaced relation to each other, feeding means in connection 45 with the lower apertures adapted to force coating through said apertures, feeding means in connection with the upper apertures adapted to force coating through said upper apertures, a plunger reciprocably mounted in said cylinder and means for operating said feeding means and said reciprocable plunger in their proper sequence.

2. A machine of the class described, including a hopper provided with downwardly converging walls, a cylinder positioned vertically in said hopper provided with oppositely disposed apertures in spaced relation to each other, feeding means in connection 60 with the lower apertures adapted to force coating through said apertures, feeding

means in connection with the upper apertures adapted to force coating through said upper apertures, a plunger reciprocably mounted in said cylinder means for operating said feeding means and said reciprocable plunger in their proper sequence and a conveyer intermittently and downwardly and upwardly operated for supporting a candy center and conveying the same from the lower end of said cylinder.

3. A coating machine, including a candy center conveyer, means for supporting said center, means for forcing coating substance below and above said center and means engaging the outer surface of said coating all 75 operated in their proper sequence and means intermittently and upwardly and downwardly operated for supporting and conducting said center and coating.

4. A coating machine, including a candy center conveyer, means for supporting said center, means for forcing coating substance below and above said center, means engaging the outer surface of said coating all 80 operated in their proper sequence and means intermittently and upwardly and downwardly operated for supporting said center and coating and a receptacle for holding said coating substance around and contiguous with said 85 operating parts.

5. A machine of the class described, including a fluid receptacle, a cylinder mounted vertically therein provided with apertures near its lower end and other apertures spaced apart above said first mentioned apertures, means for forcing fluid through said lower apertures, means for conveying a candy center into said cylinder above said lower fluid apertures, means for forcing fluid into said cylinder above said candy center and means 90 for engaging the fluid above said candy center whereby the coating is properly shaped and means for intermittently operating all of said means in their proper sequence.

6. A machine of the class described, including a fluid receptacle, a cylinder mounted vertically therein provided with apertures near its lower end and other apertures spaced apart above said first mentioned apertures, means for forcing said fluid through 100

said lower apertures, means for conveying a candy center into said cylinder above said fluid, means for forcing fluid into said cylinder above said candy center and shaping means for engaging the fluid above said candy center whereby the coating is properly shaped, means for intermittently operating 110 all of said means in their proper sequence and a conveyer intermittently operated, adapted to support the center member while 120 being formed and for removing the same.

7. A machine of the class described, including a fluid receptacle, a cylinder mounted vertically therein provided with apertures near its lower end and other apertures 125

spaced apart above said first mentioned apertures, means for forcing fluid through said lower apertures, means for conveying a candy center into said cylinder above said fluid, means for forcing fluid into said cylinder above said candy center and shaping means for engaging the fluid above said candy center whereby the coating is properly shaped, means for intermittently operating all of said means in their proper sequence, a conveyer intermittently operated, adapted to support the center member while being formed and for removing the same, means revolubly mounted in said forming means for separating the coating from said forming means and means for operating the same in its proper sequence.

8. A machine of the class described, including a fluid receptacle, a cylinder positioned therein provided with apertures adapted to receive the fluid from said receptacle, means separately actuated for forcing the fluid from said fluid receptacle through the separate apertures into said cylinder, a plunger member reciprocably mounted in said cylinder, provided with a coating forming portion on its lower end, means for engaging the candy center for supporting the same and means for operating all of said means in their proper sequence.

9. A machine of the class described, including a fluid receptacle, a cylinder positioned therein provided with apertures adapted to receive the fluid from said receptacle, means separately actuated for forcing the fluid from said fluid receptacle through the separate apertures into said cylinder, a plunger member reciprocably mounted in said cylinder provided with a coating forming portion on its lower end, means for engaging the candy center for supporting the same, means revolubly mounted in said forming portion of said plunger adapted to separate the fluid coating from said forming portion in its revolution and means for operating all of said means in their proper sequence.

10. A machine of the class described, including a fluid receptacle, a cylinder positioned therein provided with apertures adapted to receive the fluid from said receptacle, separate means separately actuated for forcing the fluid from said fluid receptacle through said apertures into said cylinder, a plunger member reciprocably mounted in said cylinder, provided with a coating forming portion on its lower end, means for engaging the candy center for supporting the same, means revolubly mounted in said forming portion of said plunger adapted to separate the fluid coating from said forming portion in its revolution and intermittently operated conveying means for conducting candy centers to said cylindrical member

and the finished product from said cylindrical member and means for operating all of said means in their proper sequence.

11. A machine of the class described, including a fluid receptacle provided with downwardly converging walls, a cylinder positioned therein provided with a plurality of oppositely disposed fluid receiving apertures spaced apart and with fluid exit apertures at the lower end of said cylinder, means mounted in said fluid receptacle for forcing the fluid through said apertures into said cylinder, a conveyer means intermittently and upwardly and downwardly operated for supporting and conveying the candy center and fluid coating from the lower end of said cylinder and a plunger member provided with a coating forming portion on its lower end reciprocably mounted in said cylinder, adapted to engage and compress the center and coating whereby the surplus passes out through the exit apertures.

12. A machine of the class described, including a fluid receptacle provided with downwardly converging walls, a cylinder positioned therein provided with a plurality of oppositely disposed fluid receiving apertures spaced apart and with fluid exit apertures at the lower end of said cylinder, means mounted in said fluid receptacle for forcing the fluid through said apertures into said cylinder, a conveyer means intermittently and upwardly and downwardly operated for supporting and conveying the candy center and fluid coating in the lower end of said cylinder, a plunger member provided with a coating forming portion on its lower end reciprocably mounted in said cylinder, adapted to engage and compress the center and coating whereby the surplus passes out through the exit apertures.

13. A machine of the class described, including a fluid receptacle provided with downwardly converging walls, a cylinder positioned therein provided with a plurality of oppositely disposed fluid receiving apertures spaced apart and with fluid exit apertures at the lower end of said cylinder, means mounted in said fluid receptacle for forcing the fluid through said apertures into said cylinder, a conveyer means intermittently and upwardly and downwardly operated for supporting and conveying the candy center and fluid coating in the lower end of said cylinder and a plunger member provided with a coating forming portion on its lower end reciprocably mounted in said cylinder, adapted to engage and compress the center and coating whereby the surplus fluid passes out through the exit apertures and means for operating all of said operating mechanism in their proper sequence.

14. The herein described method of coating centers consisting in first positioning the

- fluid coating, then positioning the candy center thereon, then forcing fluid coating over said candy center, then compressing the fluid coating around said candy center.
- 5 15. The herein described method of coating centers consisting in first positioning the fluid coating, then positioning the candy center thereon, then forcing fluid coating over said candy center, then compressing the fluid coating around said candy center and then 10 smoothing the outer surface of said fluid coating.

In testimony whereof, we have hereunto set our hands at San Diego, California, this 12th day of January, 1920.

IRA SHAFFER.
CHARLES A. SMALL.
